UNITED STATES PATENT OFFICE.

FRIEDRICH MÜLLER, OF VIENNA, AUSTRIA.

DEVICE FOR SUPPLYING FUEL TO INTERNAL-COMBUSTION ENGINES.

Application filed August 9, 1921. Serial No. 491,008.

(GRANTED UNDER THE PROVISIONS OF THE ACT OF MARCH 3, 1921, 41 STAT. L., 1313.)

To all whom it may concern:

Be it known that I, FRIEDRICH MÜLLER, a citizen of the Republic of Switzerland, residing at IV Prinz Eugenstrasse 80, Vienna, Austria, have invented a Device for Supplying Fuel to Internal-Combustion Engines (for which I have applied for patents as follows: Austria, filed Sept. 25, 1917; Germany, filed June 22, 1920; Hungary, June 26, 1920; 5 Czechoslovakia, Aug. 6, 1920; Poland, Oct. 23, 1920; Switzerland, March 29, 1921; Italy, March 29, 1921; Belgium, March 30, 1921; France, March 31, 1921; and England, April 18, 1921), of which the following is a specification.

The invention relates to internal combustion engines having fuel pumps, which work at very high speeds, such for instance as the engines of power driven vehicles. The object of the invention is to provide for a correct supply of fuel to the working cylinders, even at the highest speeds occurring in practice and to ensure such supply. The fuel pump, when it goes beyond a certain speed 20 limit, works inaccurately and irregularly. The pump valves do not open and close at the right time as the valve springs are not capable of overcoming the forces set up by the inertia of the valves due to the rapid alternations in the direction of motion and as the column of fuel sucked up by the pump does not keep pace with the piston movement. The quantities of fuel delivered at each delivery stroke will therefore differ 25 and consequently there will be a diminution in the output and the engine will run jerkily.

The invention consists in the number of delivery strokes of the fuel pump being smaller than the number of fuel injections or 30 the number of revolutions of the engine, for which both continuously running pumps (centrifugal pumps or the like) and intermittently working pumps (piston pumps or the like) may be used, which deliver the fuel 45 to a pressure accumulator.

The regulation of the quantities of fuel passing under pressure from the pump to the working cylinders is effected according to the invention by a measuring device operated by hand or by a governor and located 50 between the fuel pressure space and the points of injection, which causes the fuel to be distributed to the cylinders in accurately measured quantities. Such a measuring de-

vice makes it possible to use only one pump 55 or one pump piston, even with multi-cylinder engines, provided that the diameter and stroke are sufficiently great. By this means the construction of the pump is simplified and more particularly the number of pump 60 valves will be considerably reduced.

According to the invention at any load and at any speed of the engine the fuel will be distributed to the separate cylinders in a very accurate and uniform manner. Owing 65 to the smaller number of strokes of the pump the valves always open and close at the right moment and the sucked up column of fuel is able to follow the pump piston, even at the greatest number of revolutions 70 occurring in practice.

In the accompanying drawings three constructional examples of the invention are shown.

Figs. 1 and 2 are sectional views each 75 showing a fuel pump with a measuring device and

Fig. 3 is a sectional view of a special modification of a measuring device.

Figure 4 is a fragmentary section of a 80 pump and accumulator wherein regulation is by means of a controlled suction valve instead of a variable stroke pump piston.

Figure 5 is a section on the line 55 of 85 Figure 4.

In Figure 1:—1 is the fuel pump, 2 the pump piston, 3 the fuel pressure space, in which the fuel is put under pressure by a spring loaded piston 4. The fuel is conveyed during the suction stroke of the pump, 90 which, in the example shown in the drawing, is effected automatically by means of a spring 10, through a pipe 11 into the pump space 12 and during the compression stroke by means of a pressure valve 12', into the 95 pressure space 3, which always contains a greater amount of fuel than is necessary for one delivery stroke of the pump. The delivery stroke of the pump takes place for instance directly by means of a cam 14, 100 which is fixed on the driving shaft 13 and the inclined surface 15 of which presses on a roller 16 mounted on the pump piston and thereby moves the piston in the downward direction. 105

The fuel is pressed in the pressure space 3 by the spring loaded piston 4 and the latter is moved in the upward direction by

the fuel. Through this motion one arm of a double-armed lever 17 is raised, which limits the stroke of the pump piston 2, the stroke becoming less in proportion as less fuel is used in the engine. On the fuel delivery pipe 18 being cut off, the spring loaded piston 4 comes into its extreme position, in which the stroke of the piston is equal to zero and the engine is thrown out of operation. By turning a hand lever 19 to the left the piston 4 can be fixed in this position. When starting, the lever 19 is again put into the position shown in the drawing and the fuel will immediately be under the injection pressure. If, when starting, there is no fuel in the pump, the pump may be operated by means of the lever 17, which can be fitted with a handle, and the pressure space 3 will be filled with fuel.

20 The fuel pump delivers the fuel to a measuring device 5, which distributes the fuel in equal quantities to the working cylinders, which are connected to the measuring device. In the example shown in the drawing the measuring device is fitted for this purpose with chambers 20, 21, 22 and 23, which can take in a variable amount of fuel and the number of which is equal to the number of working cylinders or may be less than this number. These chambers take in the required amount of fuel before each injection period, the fuel being put under pressure in each chamber by spring loaded pistons 6, 7, 8, 9 so that, on the injection valves lifting, the fuel will be forced by the piston action into the working cylinder. The regulation is effected by a separate or joint displacement of the stroke limiting means of the spring loaded pistons 6, 7, 8 and 9, the length of stroke of which can be varied, for instance by an eccentric shaft 25, which is adapted to be turned by the hand lever 24. The pistons move in the downward direction only as far as the said shaft allows. In the position shown in the drawing, in which the engine is out of operation, the eccentric shaft 25 prevents any fuel being taken in, the pistons being in their inner extreme position, thereby closing the fuel delivery pipe in the manner of valves. The more the shaft is turned out of the position shown, the further can the spring loaded pistons move outwards and the greater will be the amount of fuel injected.

25 In the example shown in the drawing the supply of fuel to the measuring apparatus is controlled by a rotary valve, which in the drawing is formed by the driving shaft 13 of the pump. The valve has a bore 26, which communicates with the fuel delivery pipe 18 and from which the holes 27, 28, 29 and 30, leading to the piston spaces, branch off. The piston spaces are filled with fuel at the moment in which these holes com-

municate with the ducts leading to the piston seats. The fuel is caused to pass into the working cylinders through the action of the springs loading the pistons on the lifting of the control valves 31, 32, 33 and 34, which can at the same time be used as injection valves.

30 Fig. 2 shows a pump having a float for regulating the output, which is formed as a pressure regulator for varying the output of the pump, either by varying the stroke of the pump or by altering the time during which the suction valve of the pump is open. *a* is the plunger of the pump, *b* the fuel compression space and *c* the float. The plunger of the pump is positively operated during the suction stroke by a cam *g*, which is fixed on the driving shaft *e* and acts on a lever *f*, and during the delivery stroke automatically by a spring *h*. The float *c* in the fuel compression space is intended for varying the stroke of the pump plunger. Upon the motion of the fuel in the compression space increasing, the float will force a lever *i*, up, whereby the stroke of the pump will be limited in accordance with the output of the engine. The fuel is fed to the combustion spaces through a measuring device, which is formed as a throttling valve *d*, according as this valve is more or less opened by a hand wheel *k*, corresponding to the power required, a greater or less quantity of fuel will pass into the working cylinders.

35 In the constructional example according to Figure 3, the measuring device consists of a rotary valve fitted between the injection valve and the injection ducts. The injection valve is marked *A*, the rotary valve *B* and the valve casing *C*. The injection valve rotates and is driven by worm wheels *D* and *E*. The supply of fuel, which flows to the point of injection through the bore *F* in the valve body, is controlled at the valve seat by the bore *G* leading to the valve seat being caused to communicate during the injection period with the holes *H* and *K* in the rotary valve and with the injection ducts *L* and *M*. In order to regulate the quantities of fuel passing from the pump to the working cylinders, the rotary valve *B* is turned by means of a hand lever *N*. This turning causes a reduction of the passage for the fuel between the valve and the injection ducts and consequently a throttling of the fuel. This movement can also vary the beginning and the end of the injection periods or the time during which the valve is open, according to the direction in which the rotary valve is turned relative to the injection valve.

40 The modification of Figures 4 and 5 is intended to illustrate a control of the pump deliveries by means of a controlled suction valve rather than by means of the variable

stroke pump illustrated in Figure 1. Like parts in the figure bear like numbers. In this modification the plunger 2 has a constant stroke at all times, drawing fuel from the case 40 through an automatic suction valve 41 and discharging through a valve 42 into the accumulator chamber 3. As the accumulator piston 4 rises it lifts a lever 43 fulcrumed at 44, the other end of the lever being connected by suitable adjustable linkage 45 with means for lifting the suction valve 41 off its seat after a predetermined lift of the piston 4, thus rendering the pump 2 ineffective although it continues to suck and discharge fuel.

Having now particularly described and ascertained the nature of my said invention and in what manner the same is to be performed, I declare that what I claim is:—

20 1. In a fuel-supply for multi-cylinder engines, the combination of a fuel-pump, a main pressure-reservoir co-operating therewith, an auxiliary metering pressure-reservoir of variable capacity adapted to communicate with said main pressure-reservoir and with the engine-cylinders, and automatic valve-means controlling the timing of the passage of fuel from said main pressure-reservoir to said auxiliary pressure-reservoir.

25 2. In a fuel-supply for multi-cylinder engines, the combination of a fuel-pump, a main pressure-reservoir co-operating therewith, an auxiliary metering pressure-reservoir of variable capacity adapted to communicate with said main pressure-reservoir and with the engine-cylinders, automatic valve-means controlling the distribution of fuel from said main pressure-reservoir to said auxiliary pressure-reservoir, and independent valve means adapted to control the passage of fuel from said auxiliary pressure-reservoir to the engine-cylinders.

30 3. In a fuel-supply for multi-cylinder engines, the combination of a fuel-pump, a main pressure-reservoir co-operating therewith, an auxiliary metering pressure-reservoir of variable capacity adapted to communicate with said main pressure-reservoir, and comprising a plurality of independent pressure-chambers, each of which is adapted to co-operate with its respective engine-cylinder, and automatic valve-means controlling the distribution of fuel from said main pressure-reservoir to said pressure-chambers, successively.

35 4. In a fuel-supply for multi-cylinder engines, the combination of a fuel-pump, a main pressure-reservoir co-operating therewith, an auxiliary metering pressure-reservoir of variable capacity adapted to communicate with said main pressure-reservoir, and comprising a plurality of independent pressure-chambers, each of which is adapt-

ed to co-operate with its respective engine-cylinder, automatic valve-means controlling the distribution of fuel from said main pressure-reservoir to said pressure-chambers, successively, and independent valve-means 70 adapted to control the passage of fuel from said pressure-chambers, successively, to their respective engine-cylinders.

5. In a fuel-supply for multi-cylinder engines, the combination of a fuel-pump, a main pressure-reservoir co-operating therewith, an auxiliary metering pressure-reservoir of variable capacity adapted to communicate with said main pressure-reservoir and with the engine-cylinders, automatic 75 valve-means controlling the distribution of fuel from said main pressure-reservoir to said auxiliary pressure-reservoir, and independent valve-means adapted to control the passage of fuel from said auxiliary pressure-reservoir to the engine-cylinders, said independent valve-means constituting the fuel-injection valves of the engine-cylinders.

6. In a fuel-supply for multi-cylinder engines, the combination of a fuel-pump, a main pressure-reservoir co-operating therewith, an auxiliary metering pressure-reservoir of variable capacity adapted to communicate with said main pressure-reservoir, and comprising a plurality of independent 90 pressure-chambers, each of which is adapted to co-operate with its respective engine-cylinder, automatic valve-means controlling the distribution of fuel from said main pressure-reservoir to said pressure-chambers, successively, and independent valve-means adapted to control the passage of fuel from said pressure-chambers, successively, to their respective engine-cylinders, said independent valve-means constituting 95 the fuel-injection valves of the engine-cylinders.

7. In a fuel-supply for multi-cylinder engines, the combination of a fuel-pump, a main pressure-reservoir co-operating therewith, an auxiliary pressure-reservoir adapted to communicate with said main pressure-reservoir, and comprising a plurality of independent pressure-chambers, each of which is adapted to co-operate with its respective 110 engine-cylinder, means for adjusting the capacity of said pressure-chambers, and automatic valve-means controlling the distribution of fuel from said main-pressure reservoir to said auxiliary pressure-chambers, successively.

8. In a fuel-supply for multi-cylinder engines, the combination of a fuel-pump, a main pressure-reservoir co-operating therewith, an auxiliary pressure-reservoir adapted to communicate with said main pressure-reservoir, and comprising a plurality of independent pressure-chambers, each of which is adapted to co-operate with its respective 115 engine-cylinder, cam-controlled means for 120

adjusting the capacity of said pressure-chambers, and automatic valve-means controlling the passage of fuel from said main pressure-reservoir to said auxiliary pressure-chambers, successively.

9. In a fuel-supply for multi-cylinder engines, the combination of a fuel-pump, a main pressure-reservoir co-operating therewith, an auxiliary pressure-reservoir adapted to communicate with said main pressure-reservoir, and comprising a plurality of independent pressure-chambers, each of which is adapted to co-operate with its respective engine-cylinder, a spring-pressed piston in each pressure-chamber, and valve-means controlling the passage of fuel from said main pressure reservoir to said auxiliary pressure-chambers, successively.

10. In a fuel-supply for multi-cylinder engines, the combination of a fuel-pump, a main pressure-reservoir cooperating therewith, an auxiliary pressure-reservoir adapted to communicate with said main pressure-reservoir, and comprising a plurality of independent pressure-chambers, each of which is adapted to co-operate with its respective engine-cylinder, a spring-pressed piston in each pressure-chamber, means for adjusting the play of said pistons, and valve means controlling the passage of fuel from said main pressure-reservoir to said auxiliary pressure-chambers, successively.

11. In a fuel-supply for multi-cylinder engines, the combination of a fuel pump, a main pressure-reservoir co-operating therewith, an auxiliary pressure-reservoir adapted to communicate with the engine-cylinders, a valve controlling the passage of fuel from said main pressure-reservoir to said auxiliary pressure-reservoir, and a driving-shaft operating the pump on the working stroke thereof, said valve being carried by said driving-shaft.

12. In a fuel-supply for multi-cylinder engines, the combination of a fuel-pump, a main pressure-reservoir co-operating therewith, an auxiliary pressure-reservoir adapted to communicate with the engine-cylinders, a valve controlling the passage of fuel from said main pressure-reservoir to said auxiliary pressure-reservoir, and a rotary driving-shaft operating the pump on the working stroke thereof, said valve being formed on one end of said driving-shaft.

13. In a fuel-supply for multi-cylinder engines, the combination of a fuel-pump, a

main pressure-reservoir co-operating therewith, a spring-pressed piston in said main pressure-reservoir, an auxiliary pressure-reservoir adapted to communicate with the engine-cylinders, a valve controlling the passage of fuel from said main pressure-reservoir to said auxiliary pressure-reservoir, a driving-shaft for operating the pump on the working stroke thereof, and a lever connected with said piston and with the pump-piston for automatically varying the suction-stroke of the latter.

14. In a fuel-supply for an internal-combustion engine, the combination of a fuel-pump, a main pressure-reservoir cooperating therewith, an auxiliary pressure-reservoir adapted to communicate with said main pressure-reservoir and with the engine-cylinder, and automatic mechanism for isolating the auxiliary pressure-reservoir from said main pressure-reservoir and from the engine-cylinder, alternately.

15. In a fuel-supply for multi-cylinder engines, the combination of a fuel-pump, a main pressure-reservoir co-operating therewith, means in connection with said reservoir adapted to control the volume of fuel supplied by said pump an auxiliary pressure-reservoir adapted to communicate with said main pressure-reservoir and comprising a plurality of independent pressure-chambers, each of which is adapted to co-operate with its respective engine-cylinder, and spring loaded pistons in said auxiliary pressure-chambers for placing the fuel therein under pressure, independently of the main pressure-reservoir.

16. In a fuel-supply for multi-cylinder engines, the combination of a fuel-pump, a main pressure-reservoir co-operating therewith, an auxiliary pressure-reservoir adapted to communicate with said main pressure-reservoir and comprising a plurality of independent pressure-chambers, each of which is adapted to co-operate with its respective engine-cylinder, spring loaded pistons in said auxiliary pressure-chambers for placing the fuel therein under pressure, independently of the main pressure-reservoir, and means for controlling the distribution of fuel from said main pressure-reservoir to said auxiliary pressure-chambers, successively.

Vienna, Austria, July 18, 1921.

FRIEDRICH MÜLLER.
